F. C. ORR

SPRINKLING DEVICE

Filed April 20, 1925

INVENTOR,
FINGAL C. ORR.
By Martin Smith Atty.

UNITED STATES PATENT OFFICE.

TINGAL C. OBB, OF LOS ANGELES, CALIFORNIA.

SPRINKLING DEVICE.

Application filed April 20, 1935. Serial No. 24,449.

My invention relates to a sprinkler or water distributing device of the rotary arm type that is especially designed for use on lawns, gardens, orchards, golf courses, and in connection with fire protection systems that are installed in and around buildings.

The principal objects of my invention are, to generally improve upon and simplify the construction of the existing forms of rotary arm sprinklers; to provide a device wherein the force of pressure of the water or liquid that passes through said device, is utilized for imparting a continuous or intermittent rotary movement to the arm that carries the spray nozzle; further, to provide a device of the character referred to that is capable of ready adjustment to suit different conditions, and further, to provide a sprinkler that may be economically produced and installed and which is wholly automatic in its operation and very effective in performing its intended functions.

With the foregoing and other objects in view, my invention consists in certain novel features of construction and arrangement of parts that will be hereinafter more fully described and claimed and illustrated in the accompanying drawings in which:

Fig. 1 is an elevational view of a sprinkler of my improved construction.

Fig. 2 is a plan view of the nozzle end of the main sprinkler arm.

Fig. 3 is an enlarged vertical section taken approximately on the line 3-3 of Fig. 1.

Fig. 4 is an enlarged detail section taken on the line 4-4 of Fig. 1.

Fig. 5 is a sectional view of the jet nozzle that is arranged on the end of one of the branches of the secondary rotary arm.

Fig. 6 is a cross section taken on the line 6-6 of Fig. 5.

Referring by numerals to the accompanying drawings, which illustrate a practical embodiment of my invention, 10 designates a tubular arm, from the intermediate portion of which projects a nipple 11, that is journaled for rotation in a tubular bearing 12, and the latter being secured in any suitable manner to a water or other liquid supply pipe 13.

A watertight joint is formed between nipple 11 and its bearing 12 by locating a collar 14 on the lower end of said nipple and

arranging a packing ring or gasket 15 between said collar and the lower end of said nipple.

One part of arm 10, to the side of nipple 11 is bent upwardly so as to occupy an inclined angular plane relative to the plane occupied by said arm 10 and fitted onto the end of this angularly bent terminal portion is a jet nozzle 16.

Secured to the opposite end of arm 10 is an elbow or fitting 17, in which is arranged a bearing 18 for an auxiliary rotating sprinkler head that includes a nipple that is alike in construction to, though smaller than nipple 11. Secured to the upper end of nipple 11 is a T union 20 having one of its horizontal arms inclined slightly upward, and adjustably secured to said inclined arm is a short tubular arm 21, that is provided at its outer end with a small jet nozzle 22.

Secured to the other horizontally disposed arm of union 20 is a horizontally disposed tubular member 23, on the outer end of which is screw-seated a cap 24 that is provided in its side with a laterally disposed jet opening 25 that occupies an angle of approximately 45° relative to a horizontal plane.

The centers of gravity of the arms 21 and 23 are preferably disposed so that they are out of balance with each other and relative to the axis formed by nipple 17 and bearing 18, and, to obtain best results under practically all conditions, the two parts of main arm 10 on opposite sides of the axis formed by nipple 11 and bearing 12 counterbalance each other.

Thus, the device will function properly regardless of the position of said axis.

Where it is desired to use my improved device as an ordinary sprinkler of the arm type, it is only necessary to rotate that portion of main arm 10 that has the bent end, a slight distance to the right or left so as to position the bent end that carries nozzle 16 in a plane that is slightly inclined with respect to the vertical plane occupied by said arm 10. (See Fig. 2.)

The reaction of the jet of water issuing from nozzle 16 will cause the main arm 10 to rotate about its axis (the nipple 11 and bearing 12) and, in so doing, the auxiliary arm comprising parts 21 and 23 will be carried

around by said main arm 10 without rotating on the axis composed of parts 18 and 17.

The jets of water that issue from jet nozzle 22 and the lateral jet opening 25 will cover

5 the area immediately adjacent to the axis of the main arm and within the circular area covered by the jet issuing from nozzle 16.

When it is desired to cause the device to operate as a sprinkler of the intermittent or 10 step by step rotary type, it is only necessary to adjust auxiliary nozzle 22 or cap 24 having jet nozzle 25, or both of them, so that the jets issuing from them will react at an angle relative to the vertical plane occupied by the 15 auxiliary arm and its axis, and such reaction will cause the auxiliary arm to rotate upon its axis independently of the rotation of the main arm.

This independent rotation of the auxiliary 20 arm will, at certain points in the rotation of the main arm interfere therewith or react thereon, by virtue of the fact that, it is a natural law that a moving mass has a tendency to move in a straight line, where an opposing 25 force as insufficient to prevent it from so moving.

The reactionary thrust produced by the auxiliary arm comprising parts 21 and 23 has the effect of causing the main arm to 30 hesitate or waver slightly during its rotary travel, but it travels ahead in the direction in which the arm is rotating a slight distance further than it is retarded and thus the main arm travels or rotates with an intermittent or step by step movement.

The effort of the action just noted, causes the jet of water that issues from nozzle 16 to travel through a practically straight radial path from the axis of rotation of the 40 main arm, thus approaching in so far as is possible, the ideal results sought for in devices of the character to which my invention relates, namely, maximum coverage without resorting to the use of gearing or other complicated mechanism.

As hereinbefore stated, the jets of water that issue from the jet nozzle 22 and jet opening 25 cover that portion of the ground within the circular area covered by main 50 nozzle 16.

Thus it will be seen that I have produced an automatically acting sprinkling device that is relatively simple in structure, capable of being easily and cheaply produced, readily adjusted so as to rotate with either an even or intermittent movement and which may be advantageously used wherever it is desired to effect a thorough and even distribution of water throughout a comparatively large circular area.

It will be understood that minor changes in the size, form and construction of the various parts of my improved sprinkling device may be made and substituted for those 65 herein shown and described without depart-

ing from the spirit of the invention, the scope of which is set forth in the appended claims.

I claim as my invention:

1. In a sprinkling device a tubular arm 70 mounted to rotate on a vertical axis intermediate its ends, one end of said tubular arm being bent upwardly so as to occupy an inclined plane, a jet nozzle carried by the end of said bent end portion so as to discharge a substantially radial jet, a supply pipe to which the tubular arm is connected, an auxiliary tubular arm mounted for rotation on a vertical axis at the opposite end of the first-mentioned tubular arm and having 80 communication therewith, a portion of said auxiliary tubular arm occupying a horizontal plane and provided at its outer end with a jet orifice that is inclined relative to a horizontal plane and which is disposed substantially 85 at right angles to the axis of said auxiliary arm, the opposite portion of said auxiliary arm occupying an inclined plane and terminating in a jet nozzle.

2. In a sprinkling device, a tubular member 90 mounted to rotate on a vertical axis intermediate its ends, a supply pipe for said tubular member, a jet nozzle at one end of said tubular member and adapted to discharge a substantially radial jet, an auxiliary 95 sprinkler mounted for rotation on a vertical axis at the opposite end of said tubular member and having communication therewith, both ends of which auxiliary tubular member are provided with discharge openings, 100 one of which is disposed substantially at right angles to the other and positioned so that the jet issuing therefrom will through reaction cause rotation of said auxiliary arm.

3. In a sprinkling device, a main hollow 105 arm mounted to rotate on an axis and having branches extending in opposite directions from said axis, said hollow arm having communication with a supply pipe, a main nozzle arranged at the outer end of said arm, 110 said main nozzle being of such proportions as to permit the main volume of water passing through the sprinkling device to discharge from said nozzle in the form of a substantially radial jet, an auxiliary hollow 115 arm mounted for rotary movement on said main arm to one side of the axis thereof and having communication with said main arm, said auxiliary hollow arm having a jet opening to permit the discharge of water for the 120 purpose of sprinkling the inner area of the ground over-reached by the discharge from the main nozzle and for the purpose of imparting, by virtue of the discharge of water from the jet orifice in the auxiliary arm, a rotary movement to said auxiliary hollow arm and which rotary movement causes by 125 the reactionary forces developed the intermittent or wavering rotary movement of the entire device around the axis of the main

hollow arm for the purpose of sprinkling all of the ground within the effective radius of the device.

4. In a sprinkling device, the combination with a water supply pipe, of a main hollow arm mounted for rotation on said supply pipe and having branches extending in opposite directions therefrom, one end of which main hollow arm having an upwardly inclined main jet orifice disposed so as to discharge a main stream of sprinkling water in a substantially radial jet to the greatest possible distance from the axis of rotation of the device, an auxiliary hollow arm

mounted for rotation on said main arm on the opposite side of the axis thereof from the inclined jet orifice and having communication with said main arm, said auxiliary arm having at one end a jet orifice arranged so as to discharge a stream of water throughout the inner area of the ground over-reached by the discharge of water from the jet orifice of the main hollow arm and one end of said auxiliary arm being provided with a reactionary jet orifice.

In testimony whereof I affix my signature.

FINGAL C. ORR.
